2,223,254

DEGLAZING MACHINE FOR LEATHER SHOES

Guy L. Hite, Kearney, Nebr.

Application April 12, 1940, Serial No. 329,393

8 Claims. (Cl. 12—1)

This invention relates to a machine designed primarily for the deglazing of leather shoes, but it is to be understood that a machine, in accordance with this invention, is for use in any connection for which it may be found applicable.

The invention aims to provide, in a manner as hereinafter set forth, a machine for expeditiously and thoroughly deglazing shoes.

The invention further aims to provide, in a manner as hereinafter set forth, a machine for removing the pigment from out of the leather of a shoe for the purpose of preparing the leather to receive another color of pigment or shoe dye.

The invention further aims to provide, in a manner as hereinafter set forth, a machine for the purpose referred to which is simple in its construction and arrangement, strong, durable, compact, thoroughly efficient in the use intended thereby, readily assembled, and comparatively inexpensive to manufacture.

Embodying the aims aforesaid and others which may hereinafter appear, the invention consists of the novel construction, combination and arrangement of parts as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is a front elevation of a deglazing machine in accordance with this invention.

Figure 2 is a top plan view of the machine.

Figure 3 is a section on line 3—3 Figure 1.

Figure 4 is a section on lines 4—4 Figure 2, and

Figure 5 is a section on line 5—5 Figure 1.

The machine includes a rectangular base 5 having mounted thereon transversely thereof a prime mover for driving the shiftable elements of the machine. The prime mover is in the form of an electric motor 6 having its shaft 7 extended at one end, as at 8; such extended end has a grooved pulley 9 fixed thereto and bodily rotating therewith.

Spaced forwardly of the motor 6 and secured upon the base 6 is a riser 10 of rectangular form which constitutes a support for the lower ends of a pair of spaced parallel standards 11 having bearings 12 at their upper ends. The standards 11 are spaced inwardly from the ends of and are fixedly secured at their lower ends on the upper face of the riser 10. Mounted on and secured at their lower ends to the upper face of the riser 10 is a front and a rear post 13, 14 re-

spectively. The lower ends of the posts 13, 14 are spaced inwardly of the front edge of the riser 10. The post 13 is of greater height than and spaced forwardly from the post 14. Mounted upon and suitably secured to the riser 10 is a combined coupling and bracing member 15 for the posts 13, 14. The member 15 bears against the lower portions of the front side faces and has its ends fixedly secured to the posts 13, 14 by the holdfast devices 16.

Journalized in and extended from the bearings 12 is a power transmitting shaft 17 having fixed to one of its ends a grooved pulley 18 of greater diameter than and which aligns with the pulley 9. Fixed to the other end of shaft 17 is a disc 19 provided with a crank pin 20 eccentrically thereof. Travelling around the pulleys 9, 18 is a power transmission belt 21 to thereby provide on the operation of the motor 6 the driving of shaft 17 at reduced speed with respect to the speed of motor shaft 8. On the driving of shaft 17 the disc 19 will be bodily carried therewith. The disc 19 is spaced inwardly from the posts 13, 14.

The machine includes an operating mechanism 22 for a reciprocatory carrier 23 for a deglazing element 24. The carrier 23 and element 24 will be more fully referred to. The mechanism 22 is driven from the crank pin 20 and it includes a pitman 25 which is pivotally connected at its inner end to and operated from the crank pin 20. The pitman 25 is connected at its outer end, as at 26, to the rear end of a reciprocatory operator 27 for the carrier 23. The operator 27 is in the form of a slide bar 28 of materially greater length than the distance between the posts 13, 14.

Secured to the inner faces of the posts 13, 14 is a pair of combined guide and supporting devices 29, 30 respectively for the operator 27. The device 29 is arranged against the upper terminal portion of the inner face of the post 13 and aligns with the device 30. The devices 29, 30 are of like form each consisting of a block 31 having its outer face arranged against the inner face of a post 13 or 14 and its rear face formed with a guide-way 32 in the form of a groove extending from one side to the other side of the block 31. The mouth of the groove is closed by a plate 33 positioned against the rear face of the block 31. The sides of block 31 and plate 33 are flush with the sides of a post 13 or 14. A block 31 and a plate 33 are secured together and to a post 13 or 14 by superposed holdfast devices 34 arranged above and below a guide-way. The operator 27 is slidably supported by the block 31, is guided

by the grooves which form the guide-ways and is retained in the latter by the plates 33. The guide-ways 32 are open at each end and align with each other.

5 The carrier 23 for the element 24 is in the form of a rectangular head 35 having a substantially convexed lower surface 36. The head 35 is provided at the intersection of its transverse and lengthwise medians with an opening 37 which 10 extends from the lower surface 36 to the upper surface 38 of the head.

15 The carrier 23 includes a shank 39 which extends rearwardly from and is integral with the rear end of head 35. The shank 39 is formed of a flat forward portion 40 of flared contour and a flat rear portion 41 of substantially ovoidal contour which merges at its forward end into the rear end of the portion 40. The portion 41 is of greater width than the operator 27.

20 The operator 27 has its forward end terminal portion mounted upon the upper face of the portion 41 of the carrier. The operator 27 and the carrier 33 are detachably secured together and for such purpose a clamping structure 42 is provided consisting of a clamp block 43 formed with a horizontal passage 44 and a vertical passage 45 of less width than and opening at its bottom into the top of the passage 44. The passages open at the front and rear sides of the block 43. 30 The latter is formed with a vertically disposed screw threaded opening 46 extending from the top of block 43 and communicating at its lower end with the passage 44 through the top of the latter.

35 The forward terminal portion of operator 27 is arranged in and extends forwardly from passage 45. The portion 41 of shank 39 is arranged within and extends from the passage 44. The operator 27 when arranged relative to the block 43 40 has its forward terminal portion extend through the passage 45. The carrier 23 when arranged relative to block 23 has the portion 41 of the shank 39 extend through the passage 44. The block 43 is arranged in encompassing relation 45 with the forward portion of the operator 27 and the rear portion of the carrier 23 and when so arranged the forward portion of the operator is superimposed with respect to the rear portion of the carrier. The structure 42 includes an adjustable clamping screw 47, which threadedly engages with the wall of opening 46, has its lower end bearing on the top of the operator 27. The screw 47 when adjusted inwardly correlates with the bottom wall of passage 44 for clamping operator 27 and carrier 23 together and to the block 43.

40 The deglazing element 24 is yieldable, of arcuate contour and formed of spaced rows 48 of spaced tufts of bristles. The upper ends of the 60 tufts of bristle of the rows 48 are secured in the lower surface 36 of the head 35 and depend from the latter.

45 The machine includes a vertically disposed container or receptacle 49 constituting a reservoir for the shoe deglazing fluid. The container 49 is removably supported laterally from and connected to the upper end of the post 13. The means for supporting and connecting the container 49 to post 13 is indicated at 50. The container 49 at its bottom is formed with a depending outlet pipe 51 formed intermediate its ends with an outlet controlling valve 52. Attached to the lower end of the pipe 51 is the upper end of a vertically disposed oscillatory flexible deglazing 70 fluid feed pipe 53 of curved form which has its 75

lower terminal portion arranged in a deglazing fluid catcher 54 of funnel-like form.

5 The catcher 54 includes a narrow hollow body part 55 formed of a rectangular upper portion 55^a and a tapered lower portion 55^b which opens centrally of its bottom 55^c into a discharge spout 56. The latter extends into the opening 37 in the head 35 of the carrier 23. The spout 56 is of a length to extend to the lower surface 36 of head 35. The discharge of the fluid is at the lower 10 surface of the head 35 directly into the deglazing element 24. The spout 56 is removably secured to the carrier 23 whereby the catcher 54 will bodily move with the carrier 23, in both directions of movement of the latter and in turn oscillate the pipe 53. The oscillation of the pipe 53 is had from the forward and rear walls of the catcher when such walls contact with the lower terminal portion of pipe 53 during the reciproca- 15 tion of the carrier.

20 The pigment is taken out of the leather of the shoe by subjecting the shoe upper to the action of the deglazing element 24, when the deglazing fluid is supplied to the latter during the reciproca- 25 tion of the carrier 24 from the operator 27. The feed of the fluid to the catcher 54 is controlled by the valve 52. The feed of the fluid to element 24 during the operation of the machine is continuous. The element 24 provides a rubbing action on the leather and in connection with 30 the fluid removes the pigment.

The structure 42 permits of the carrier being readily removed from operator 27 when a change of deglazing element is desired.

What I claim is:

1. In a leather shoe deglazing machine, a horizontally disposed reciprocatory operator, a reciprocatory carrier bodily moving with and detachably connected at its inner end portion to and extended from the outer end portion of the operator, a deglazing element depending from the outer end portion of and bodily carried with the carrier, a vertically disposed open top catcher for a deglazing fluid, said catcher bodily moving with the carrier and formed with an outlet spout at its bottom having its lower portion mounted in the outer portion of the carrier and discharging into said element, and controllable means for supplying a deglazing fluid to said catcher depending into the latter from its open top.

2. In a leather shoe deglazing machine, a horizontally disposed reciprocatory operator, a carrier bodily moving with and connected at its inner end portion to and extended from the outer end portion of the operator, a deglazing element depending from the outer end portion of and bodily carried with the operator, an open top upstanding catcher for a deglazing fluid, said catcher bodily moving with the carrier and having an outlet spout at its bottom mounted in the outer portion of the carrier and discharging into said element, controllable means for supplying a deglazing fluid to said catcher, a pair of spaced parallel posts, and a pair of aligned combined guide and supporting devices for said operator fixedly secured to said posts.

3. In a leather shoe deglazing machine, a horizontally disposed reciprocatory operator, a carrier bodily moving with and connected at its inner end portion to and extended from the outer end portion of the operator, a deglazing element depending from the outer end portion of and bodily carried with the carrier, an open top upstanding catcher for a deglazing fluid, said catcher bodily moving with the carrier and hav- 75

ing an outlet spout at its bottom mounted in the outer portion of the carrier and discharging into said element, controllable means for supplying a deglazing fluid to said catcher, a pair of spaced parallel posts, a pair of aligned combined guide and supporting devices for said operator fixedly secured to said posts, one of said posts being of greater height than the other, means at the upper terminal portion of the post of greatest height for suspending said controlling means in laterally extended relation with respect to such post, and said controlling means including a depending flexible fluid feed pipe extending in and discharging the fluid into said catcher.

15 4. The invention as set forth by claim 2 having the lower surface of the outer portion of the carrier of convexed contour, and said element being secured in and depending from said surface and being of arcuate contour.

20 5. The invention as set forth by claim 3 having one of said combined guide and supporting devices located on the inner face of the post of greatest height intermediate its end and the other one of the said combined guide and supporting devices located on the upper terminal portion of the inner face of the other one of said posts.

25 6. In a leather shoe deglazing machine, a horizontally disposed reciprocatory operator, a carrier bodily moving with and connected at its inner end portion to and extended from the outer end portion of the operator, a deglazing element depending from the outer end portion of and bodily carried with the carrier, an open top upstanding catcher for a deglazing fluid, said catcher bodily moving with the carrier and having an outlet spout at its bottom mounted in the outer portion of the carrier and discharging into said element, controlling means for supplying a 30 deglazing fluid to said catcher, the outer portion of said operator disposed in superimposed rela-

tion with respect to the inner portion of the carrier, and a means encompassing the said portions of the operator and carrier for clamping such portions together.

7. In a leather shoe deglazing machine, a horizontally disposed reciprocatory operator, a carrier bodily moving with and connected at its inner end portion to and extended from the outer end portion of the operator, a deglazing element depending from the outer end portion of and bodily carried with the carrier, an open top upstanding catcher for a deglazing fluid, said catcher bodily moving with the carrier and having an outlet spout at its bottom mounted in the outer portion of the carrier and discharging into 15 said element, controllable means for supplying a deglazing fluid to said catcher, and a pair of spaced parallel stationary combined guide and supporting devices for said operator.

8. In a leather shoe deglazing machine, a horizontally disposed reciprocatory operator, a carrier bodily moving with and connected at its inner end portion to and extended from the outer end portion of the operator, a deglazing element depending from the outer end portion 25 of and bodily carried with the carrier, an open top upstanding catcher for a deglazing fluid, said catcher bodily moving with the carrier and having an outlet spout at its bottom mounted in the outer portion of the carrier and discharging into 30 said element, controllable means for supplying a deglazing fluid to said catcher, a pair of spaced parallel stationary combined guide and supporting devices for said operator, means for suspending said controlling means above the operator 35 and carrier, and said controlling means including a depending flexible fluid feed pipe having its lower terminal portion arranged in said catcher for discharging fluid therein.
